UNITED STATES PATENT OFFICE

95,908

DESIGN FOR A TEXTILE FABRIC

David F. Greenawalt, Huntingdon Valley, Pa.

Application April 16, 1935, Serial No. 56,413

Term of patent 3½ years

To all whom it may concern:

Be it known that I, David F. Greenawalt, a citizen of the United States, residing in Huntingdon Valley, county of Montgomery, and State of Pennsylvania, have invented a new, original, and ornamental Design for a Textile Fabric, of which the following is a specification, reference being had to the accompanying drawing, forming part thereof.

The figure is a plan view of a piece of textile fabric showing my new design on an enlarged scale in the ratio of 2 to 1.

The repeat unit of the design is included between the two dot and dash lines A—A and B—B.

The design is comprised of a series of parallel raised surfaces indicated by the heavy lines shown on the figure, and intercepted at regular intervals by stripes composed of miscellaneous and irregular stitches.

I claim:

The ornamental design for a textile fabric as shown and described.

DAVID F. GREENAWALT.
